R. Wilde.
Spinning Mule.

No 56,133.

Patented Jul. 3, 1866.

UNITED STATES PATENT OFFICE.

ROBERT WILDE, OF PHILADELPHIA, PENNSYLVANIA.

IMPROVEMENT IN SPINNING-MULES.

Specification forming part of Letters Patent No. **56,133**, dated July 3, 1866.

To all whom it may concern:

Be it known that I, ROBERT WILDE, of the city of Philadelphia, in the State of Pennsylvania, have invented a new and useful Improvement in Spinning-Mules; and I do hereby declare that the following is a full, clear, and exact description of the construction and operation of the same, reference being had to the accompanying drawings, making a part of this specification, in which—

Figure 1 is a side elevation, and Fig. 2 an end elevation, of a spinning-mule head, showing my said improvement applied thereto, Fig. 3 being a plan view of the detached sliding rod or bar, in connection with the weight, pulley, and the levers which immediately operate to connect and disconnect the gear-wheels of the mule-head, like letters of reference indicating the same parts when in the different figures.

The object of my improvement is to produce and apply an apparatus which will be more efficient, as well as more simple and less costly in construction, and also more durable in use, for putting the roll and scroll wheels of a spinning-mule in and out of gear during the movements of the carriage; and the nature of my said invention consists in the employment of a weight, or its equivalent, in connection with a sliding rod and levers on the mule-head and operating studs or projections on the carriage, constructed and operating substantially as hereinafter described.

In the drawings, A B is the frame of the mule-head; C, a representation of one of the positions of the carriage; D, the weight; E, the sliding rod; F, its operating-lever; G, its sustaining-lever; H, the gear-detaching lever, and I and J the two operating-studs on the end of the usual carriage.

The sliding rod E is attached to the side of the mule-head frame A B, and has two mortises or slots, e' e', in which its sustaining-lever G and its operating-lever F, respectively, work, the notched end g' of the former sustaining or holding the sliding rod E, both in its advanced and retracted positions alternately, and the lever F, passing through the slide E and extending downward, serves as a means of advancing the said slide E, and also of elevating the retracting-weight D. The opposite end of the slide E passes loosely through a boss, l, on the lower end of the usual scroll-wheel lever l', and has

a head, e², on its extreme end, whereby the said lever l' is caused to lift the usual scroll-wheel l² into gear with its pinion above, when the slide E is retracted by the weight D, which is suspended by a cord over the pulley d', as will hereinafter be described. Also, on the said slide E there is fixed a boss, e³, which has a short arm extending upward, and serving to catch against the horizontal arm n of the crank-lever n², which supports the upper end of the beveled roll-wheel o, and thus throws the latter into gear as the said slide E is retracted by the weight D, as will hereinafter be explained.

The gear-detaching lever H has one end, h', pivoted to the frame A B, while its other end is left free to be moved up and down in a guide, h², also attached to the frame. Fixed to and projecting downward from the said lever H are two curved rigid arms, h³ h⁴, of such lengths and forms that, as the end c of the carriage C passes, the stud J on the latter will first strike and pass under the arm h³, and thus elevate the lever H sufficiently to release the arm n, which is held back against the pressure of its spring n' by means of the stop h⁵ on the said lever H, and thus throw the roll-wheel o out of gear, and immediately afterward the said stud J strikes against and passes under the arm h⁴, elevates the said lever H sufficiently farther to detach the scroll-wheel lever l' from its contact with a small angular stop, h⁶, on the said lever, which latter then rests, by the said stop, on the boss l, while at the same time the scroll-wheel l², which is supported by the said lever l', falls out of gear. (See the dotted lines in Figs. 1 and 2.)

The operation of this apparatus in throwing the roll-wheel o and the scroll-wheel l² out of gear by the advancing or outgoing motion of the carriage C having now been fully described, it remains to describe its operation in throwing the said wheels again into gear. This is effected by the returning or ingoing motion of the same carriage, when its stud I, coming in contact with the retaining-lever G, moves the latter backward far enough to disengage its notch g' from its slot in the slide E, and thus permits the weight D to draw back the said slide E, and consequently, by means of its two bosses, e² e³, to force the two respective wheels l² and o into gear, as seen in the drawings.

It will be seen that this apparatus is less

complicated than the old one, that it is less liable to derangement by use, and that it is much lighter in weight, more durable, and costs less for construction and application, while it is equally if not more reliable and efficient for the purpose.

I do not desire to confine myself in its construction to the use of the weight D for retracting the slide E, and thus bringing the wheels l^2 and o into gear, as it will be obvious that a strong spring will answer as an equivalent for the same purpose, although I prefer the use of the weight, as set forth; but,

Having fully described my improvement in spinning-mules, what I claim as new therein, of my invention, and desire to secure by Letters Patent, is—

The sliding rod E, levers F, G, and H, and the weight D, or its equivalent, the same being constructed, arranged, and applied so as to operate substantially as and for the purpose described.

ROBERT WILDE.
